A. DIETSCHÉ, JR.
DISPLAY DEVICE.
APPLICATION FILED SEPT. 21, 1920.

1,412,846.

Patented Apr. 18, 1922.

Inventor,
Adolph Dietche Jr.;
By William M. Stone
his Attorney.

UNITED STATES PATENT OFFICE.

ADOLPH DIETSCHÉ, JR., OF NEW YORK, N. Y., ASSIGNOR TO AMERICAN LITHOGRAPHIC COMPANY, OF NEW YORK, N. Y., A CORPORATION OF NEW YORK.

DISPLAY DEVICE.

1,412,846.

Specification of Letters Patent. Patented Apr. 18, 1922.

Application filed September 21, 1920. Serial No. 411,758.

To all whom it may concern:

Be it known that I, ADOLPH DIETSCHÉ, Jr., a citizen of the United States, and a resident of New York, borough of Queens, in the county of Queens and State of New York, have invented certain new and useful Improvements in Display Devices, of which the following is a specification.

This invention relates to display devices and has for its object to provide a device of the class specified of simple construction, which can be laid flat for shipment and which can be erected into display condition with little effort.

To these ends my improvements comprise features which are illustrated in their preferred embodiment in the drawing accompanying this specification, wherein:

Figure 1 is a perspective view of my improved display device erected. Fig. 2 is a plan view of the device with all members thereof laid out flat in condition for shipping or assembling. The scale of Fig. 2 is about two-thirds that of Fig. 1.

My improvements are illustrated as showing one adaptation thereof, embodying a fictitious container, such as a box for candy or the like. Said device preferably comprises top panel member 2, to the opposite ends at lines 2^a and 2^b of which are articulated opposite side panel members 3 and 4, respectively, and to the front edge at lines 2^c of which is articulated front panel member 5. For convenience all four of said members may be formed of one integral sheet of relatively stiff material such as cardboard and which sheet may be scored along said lines 2^a, 2^b and 2^c for folding.

Preferably said side members 3 and 4 are provided with downwardly extending feet 3^a and 4^a, respectively, Fig. 1, and which feet may represent holders for the simulated box or container and are also adapted to rest on a counter or show case for supporting the device.

Said side members and front member are provided with means, respectively, for securing them together along their meeting edges; such means preferably include locking slots, as 6, in members 3 and 4, and opposite ears, such as 7, projecting from the ends of said member 5. Said slots, as 6, are preferably located in the foot portions, as 3^a of member 3, and said ears, as 7, preferably project from downwardly extending

tabs, as 8, of member 5, so that the interlocked portions of the device lie within those parts thereof representing the support.

Also, there are preferably provided opposite end wings 9 and 10, extending from the ends, respectively, of member 5 and which wings are adapted for folding within the side members, respectively, when the device is erected, for strengthening the structure.

I claim:

1. A display device consisting of a sheet of relatively stiff material folded along one longitudinal and two transverse lines, whereby a top member, opposite side members and a front member are formed, and means for interlocking said front and side members respectively when folded, said opposite side members having downwardly extending feet adapted for supporting the device in elevated position. 65

2. A display device consisting of a sheet of relatively stiff material folded along one longitudinal and two transverse lines, whereby a top member, opposite side members and a front member are formed, said side members having locking slots therethrough respectively, said front member having opposite ears for engaging said locking slots respectively of said side members, and said opposite side members having downwardly extending feet adapted for supporting the device. 75

3. In a display device the combination of a top panel member, opposite side panel members articulated to opposite ends of said top panel member, and a front panel member articulated to the front edge of said top panel member, said four members being adapted, when folded with the front edges of said side members meeting the opposite ends respectively of said front member, to represent a container, said side members having locking slots therethrough respectively, and said front member having opposite ears for engaging said locking slots respectively of said side members. 90

4. In a display device the combination of a top panel member, opposite side panel members articulated to opposite ends of said top panel member, and a front panel member articulated to the front edge of said top panel member, said four members being adapted, when folded with the front edges of said side members meeting the opposite ends respectively of said front member, to rep- 105 110

resent a container, said opposite side members having downwardly extending feet adapted for supporting the device, each of said side member feet having a locking slot 5 therethrough, and said front member having opposite downwardly extending tabs each of which is provided with an ear for engaging one of said locking slots respectively.

5. In a display device the combination of
10 a top panel member, opposite side panel
members articulated to opposite ends of said
top panel member, and a front panel mem-
ber articulated to the front edge of said top
panel member, said four members being
15 adapted, when folded with the front edges
of said side members meeting the opposite

ends respectively of said front member, to
represent a container, said opposite side
members having downwardly extending feet
adapted for supporting the device, each of 20
said side member feet having a locking slot
therethrough, said front member having op-
posite downwardly extending tabs each of
which is provided with an ear for engaging
one of said locking slots respectively, and 25
said front member having opposite end
wings adapted to be folded within the side
members respectively.

In witness whereof, I hereby affix my sig-
nature this 20th day of September, 1920.

ADOLPH DIETSCHE, JR.
